CURRENT RECTIFYING APPARATUS

Friedrich Meyer and Hans Joachim Spanner,
Berlin Halensee, Germany, assignors to Electrons, Inc., a corporation of Delaware

Application March 28, 1929, Serial No. 350,777,
and in Germany January 27, 1927

18 Claims. (Cl. 250—27.5)

This application is a continuation in part of our application Serial No. 247,316 filed 17 January 1928 as to all matters relating to Fig. 5 therein and a continuation in part of our application Serial No. 214,192 filed 19 August 1927 Patent No. 1,784,877, granted December 6, 1930 for all matters pertaining to Figures 2, 3, 4, 4a and 4b herein.

This invention relates generally to the rectifying of alternating current, and more particularly to methods and apparatus for deriving auxiliary direct or pulsating current potentials from a principal current rectifying system more or less independently of the output of the principal rectifying system.

This invention further relates to gas-filled discharge devices, and particularly to rectifiers operating with a space current discharge in a gas-filled container with the aid of an incandescent or heated electron emitting cathode.

A particular object of the invention is to direct and control the discharges necessary to current rectifying actions to prevent improperly timed discharges and discharges between the wrong electrodes.

Another object is to conserve in the matter of space needed by the device, and at the same time to provide for efficient operation.

A further object is to provide an arrangement permitting of rectifying high potential alternating currents without resorting to widely spaced electrodes and awkward constructions of the container or tube.

In rectifying systems having a direct or pulsating current output for supply to current consuming devices, it is frequently desirable to have available auxiliary potentials accompanied by small current consumption compared to the principal output to aid in proper control of the operation of either the rectifying system or the associated current consuming devices. For example, if the current rectifying device is a discharge tube, it may be desirable to have within such tube auxiliary electrodes for the purpose of influencing the space discharge, and to apply to these electrodes chosen polarities of potential of predetermined degree. Or if the rectifying system is employed in connection with a filter system to energize the plate circuits of one or more three electrode vacuum tubes of an amplifying system it may be desirable to have available one or more auxiliary potentials for application to the grid electrodes of the tubes, which potentials are ordinarily negative in character.

Another object of our invention is the provision of auxiliary electrodes so spaced with reference to the anodes that auxiliary negative potentials may be derived from the operation of the tubes to be described herein for use in establish-

ing grid biases of the various tubes of standard radio receivers.

A feature of the invention is the use of screens between and around electrodes and the use of auxiliary electrodes for directing, confining and controlling the rectifying discharges to arrive at the results desired. Another feature is the use of the relative effects of an eliminated "cathode fall" at an effective electron emitting cathode and the mean free path of electrons in a gas-filling. Simple and inexpensive construction is an additional feature.

The general operating advantages of gas-filled rectifier tubes operating with the aid of heated effective electron emitting cathodes, such as for example the well-known oxide coated cathodes of Wehnelt, the German scientist, are ably pointed out by Germershausen in an article in the June and July 1920 issues of "Helios", an electro-technical publication of Leipzig, Germany. However, Germershausen and others prior to us, have failed to arrive at satisfactory simple and inexpensive constructions for such rectifying and like discharge tubes with provisions for desirable efficiency of operation, a fact readily appreciated by examining the tubes of Germershausen illustrated in Fig. 14 of page 258 of the June 1920 issue of "Helios". The tubes shown in this figure are so-called "full wave" rectifiers. There is a heated electron emitting cathode in the central portion of the bulb co-operating with two anodes in the ends of the two arms or extensions from the main portion of the bulb, this to get wide separation between the anodes to confine the discharges alternately between the cathode and the respective anodes, and to avoid breakdown discharges between the anodes. Obviously, such a bulb is awkward and expensive in construction.

From an operating point of view it is inefficient because of the long discharge paths physically constricted in cross-sectional area, and further electrically so constricted because of the collection of electrical charges on the side walls of these paths, both of which effects make the overall drop of potential between cathode and anodes high, inconsistent and uncontrollable.

These Germershausen tubes have in them the advantage pointed out by him of substantially eliminating the so-called "cathode fall" or difference of potential in the cathode dark space, and thus eliminate this drop from the over-all potential. For example, in an argon atmosphere of about one millimeter of mercury pressure a potential component of about 130 volts is eliminated, which voltage bridging the cathode dark space is necessary to impart sufficient velocity to ions to create sufficient electron emission by bombardment from a cold electrode when such is used for starting the general ionization of the discharge path. The set of conditions above

cited for argon are probably the most favorable for easy starting with cold electrodes, so that with other conditions, such as other gases and less favorable cathode materials, the cathode fall is even higher, and under these less favorable conditions the beneficial effect of the heated electron emitting cathode is greater.

As pointed out by Germershausen, the other drop of potential components of the discharge path are small compared to the cathode fall. These other components are two in number and comprise the drop in the luminous portion of the path and the so-called "anode fall", which latter is representative of the potential needed to create ionization of the particular gas used, which in the case of argon is about 12 volts. The drop in the luminous portion depends upon the length of the discharge path, its cross-sectional area, the intensity of the discharge, the nature of the gas and the pressure of the gas. In our practice this luminous drop is of the order of a few percent of the cathode fall; that is, a few volts. In the case of the Germershausen tubes, Fig. 14 for example, the long, constricted and electrically charged paths keep this luminous drop high and inconstant because of the inconstancy of the charges on the walls with intensity of discharge current.

The obtaining of a positive auxiliary potential in the ordinary rectifying system is a comparatively simple matter. The present practice however seems to require a negative auxiliary potential more often than a positive, and this invention includes a manner that is simple and not involving complicated apparatus for securing in connection with well known rectifying systems negative potentials suitable for many common purposes, even very high negative potentials.

The several features of this invention will be best understood by a discussion in connection with the figures of the accompanying drawing.

Fig. 1 shows a so-called "full wave" rectifying system in which auxiliary electrodes are included within a rectifying tube by which is derived potentials which may be used for grid bias supply in standard radio receivers.

Fig. 2 shows in perspective a full-wave alternating current rectifier of the gas-filled heated electron emitting or thermionic cathode type in which provision is made for preventing undesired discharges between the anodes by using flat anodes shielded from each other by a heated electron emitting cathode, and having incorporated therein the auxiliary electrodes of our invention.

Fig. 3 is a modification of the arrangement shown in Fig. 2.

Fig. 4 illustrates in perspective a full-wave rectifier in which a shield is interposed between the anodes so as to separate the tube into a plurality of electrically independent discharge spaces with a single emitting cathode so located as to function with both anodes, and includes auxiliary shielding and discharge control means, and including the auxiliary electrodes of our invention.

Fig. 4a is an elevation in part of the tube shown in Fig. 4.

Fig. 4b is a plan view of the electrode arrangement shown in Fig. 4a but with the shield omitted to show the relative spacing of the cathode, the anodes and auxiliary electrodes.

Referring to Fig. 1, RT represents a rectifying discharge tube having a single filament F adapted to be heated for electron emission from a secondary winding S_1 of alternating current

transformer T, and two anodes A for alternate, or "full wave", rectification of alternating current supplied from the two extremities of the secondary winding S of the transformer T. The transformer T is indicated as having its primary winding energized from an alternating current source AC. The secondary winding S is indicated as tapped at a substantially mid or neutral point O, and the two portions shunted by the usual by-pass condensers C. The rectifier output circuit is shown to be included between the neutral point O and a neutral point on secondary winding S_1 , terminating in positive output terminal P_1 and negative output terminal P_0 , across which the usual potential dividing resistance R is connected, and along which is positioned a variable tap connected to the intermediate positive terminal P_a by-passed by condenser C_3 . To the terminal P_0 is connected a resistance R_1 , along which are connected variable taps for supplying potentials to the terminals P_a , P_a' each of which is shunted by a condenser C_2 , C_4 respectively. The resistance R_1 is shunted by a condenser C_1 . The other terminal of the resistance R_1 is connected to the auxiliary electrode E_a the exact positioning of which will be herein-after described with reference to Figs. 2-4b inclusive.

This electrode E_a cooperates with one of the anodes A A', which acts as a cathode in such co-operation, to form an auxiliary rectifying system for aiding in the production of the auxiliary potentials. By constructing the auxiliary electrode E_a small compared to the anode A, the correct sense of rectification is secured, the rectified current passing through resistance R_1 by way of points P_0 and O to the anode A, when this anode is acting as a cathode on that half of the alternating current cycle during which it is not functioning as an anode in the principal rectifier. The desired auxiliary potentials may be tapped from resistance R_1 to the terminals P_a and P_a' as shown.

The shield K in the rectifying tube RT, located as shown between the two anodes A, A', assures that there will be no discharge between the two anodes to interfere with the normal operation of this tube as a "full wave" rectifier.

In this arrangement, and utilizing terminal P_0 as a reference terminal, terminals P_a and P_1 are progressively more positive and permit substantial loads being placed thereon and terminals P_a , P_a' while not designed to carry heavy loads carry potentials progressively more negative than P_0 .

Referring now to Figs. 2-4b inclusive which show the specific types of tubes that we employ as RT in Fig. 1, there is shown a rectifier tube having the usual glass or like container 1 provided with the usual stem 2 through which the lead-in electrode wires pass as indicated in accordance with common practice. The tube is arranged for full-wave rectification by having a heated electron emitting or thermionic cathode 3 and two co-operating anodes 4' and 4'', the heating current for the cathode being supplied by way of the two conductors 9 and 10. There is a gas-filling in the tube of low pressure; for instance argon gas at about one millimeter of mercury pressure. The anodes 4' and 4'' are flat and protected relatively to one another and the cathode by the interposed cathode 3 as shown. The protection is due to the fact that the interposed cathode and its emitted cloud of electrons act as screening or shielding effects against

break-down discharges between the anodes. A break-down discharge between the two anodes would require a condition of sufficient positive ionization in the gas path between them to generally ionize the discharge path. For example, considering that phase of the alternating current cycle when anode 4' is at a maximum positive potential and anode 4'' is at a maximum negative potential, and the potential between the anodes 10 is double that between either anode and the cathode, there is a discharge by general ionization between the cathode and anode 4'. At this time the strong negative potential of anode 4'' is tending to draw to its neighborhood the positive ions from the field between the cathode and anode 4', and if it is successful in drawing sufficient positive ions to its neighborhood to energize this part of the space then a general break-down discharge will occur. However, for the 20 positive ions between the cathode and anode 4' to reach the neighborhood of anode 4'' it is necessary that they pass through the cloud of electrons continuously emitted by the cathode and the cathode's field action, and are thus subject 25 to neutralization. Therefore, if the tendency for transferring positive ions is not too strong for the electron emission of the particular cathode sufficient neutralization takes place to prevent a break-down discharge. Thus in such an arrangement as that of Fig. 2 there is a limit 30 to the amount of discharge current or rectifying action that can be had with a given emitting cathode.

There also has to be considered the possibility 35 of a reverse action or discharge between the cathode and the anode that is negative. In the case of Fig. 2 the cathode is the screen or shield, and the flat anodes are located sufficiently close to the cathode that each of the spacings between 40 the cathode and the two anodes is comparable to the mean free path of the electrons in the particular gas and pressure of it used, an effect fully explained by W. Crookes as early as about 1905 as pointed out in German Patent 209,969 filed November 10, 1908. By reason of employing a separation having this mean free path relation the electron flow from the negative anode to the cathode does not create positive ionization, so that there is no general ionization or 50 break-down discharge at this part of the system.

Herein we have placed auxiliary electrodes E_a and E_a' either or both of which may be connected to the resistance R_1 . These electrodes are represented as small spheres, although other 55 shapes may be used without departing from the spirit of our invention, and, having an area much smaller than the area of the anodes 4' 4'', the correct sense of rectification is assured, when its corresponding anode is acting as a cathode on that half of the alternating current cycle during which it is not functioning as an anode in the principal rectification scheme of the device.

Fig. 3 modifies the arrangement of Fig. 2 by 65 locating the emitting cathode 3 above the anodes 4' and 4''. Since in this arrangement the cathode is removed from its interposed position the anodes are moved closer together to arrive at the separation distance comparable to the mean free path relation to prevent a discharge therebetween. The same relation pointed out in connection with Fig. 2 as between the cathode and the two anodes is maintained. With this arrangement it is possible with not too high currents and potentials to prevent break-down discharge between the anodes and between the

cathode and non-active anode for the reasons given in connection with Fig. 2. Obviously this second arrangement produces a better exposure of the anode surfaces to the cathode for better formation of discharge paths between the cathode by way of the electron field and the alternately operating or active anodes. Herein the electrodes E_a and E_a' serve similar functions as those described with reference to Fig. 2.

Figures 4, 4a and 4b are different views of the same full-wave rectifier having two anodes 4' and 4'' shielded from each other by a screen 5, the emitting cathode comprising the two spiral elements 3' and 3'' connected in series relation and supplied with heating current by way of leads 9 and 10, this cathode arrangement being located at the top of the screen. A further screen 5' is interposed in a straight line path between the cathode 3' 3'' and anodes 4, 4' to deflect or lengthen the path of the discharge. This arrangement thus divides the tube 1 into two general discharge sections or spaces. The screen may be either of conducting material or insulating material superficially rendered conductive, a simple process for the latter being the deposit 100 thereon of the usual mirror effect resulting from getter vapor condensation accompanying the usual clean-up process in making such tubes.

The walls of the tube also have a coating of the condensed getter material which may be used 105 as screens to aid in directly and controlling the discharge by reason of the field action of electrical charges collected thereon, and for this reason it is not necessary to extend the space-dividing screens to the walls of the tube to completely 110 divide off the discharge spaces. The charges on the dividing screens and walls tend to prevent undesired discharges taking place by way of the spaces between internal screens and walls.

There is also shown an auxiliary screen 6 in 115 the space above the cathode, which may or may not be necessary depending upon the size of the space, operating voltages and currents and resulting field actions. Its purpose is to prevent positive ions on the active side of the system 120 from escaping in undesired number through this space to the inactive side. It acts as an auxiliary in this respect to the cloud of electrons above the cathode. As before stated, it need not span the space entirely if used, as the charges that collect 125 on it will co-operate with the charges that collect on the getter surface of the walls of the tube to prevent discharges by way of passages between screen and walls.

The screens 5 and 6 are shown connected to the 130 cathode by way of connections 8 and 7 respectively and the getter conducting surface on the tube walls also so connected by way of cross-connecting element 17 between the walls and the screen 5. These connections permit of controlling the degree of electrical charges collecting on these elements, and therefore the resulting field actions of these charges on the operating discharges of the tube. Under some operating 135 conditions of potential and current it is not necessary to connect the screens to the cathode or any other point of controlled potential, this because there is an inherent tendency for the positive ions in the operating discharge paths to neutralize the rapidly collecting negative charges 140 on the screens originating with the operating electrodes, so that there is a natural tendency for the screens to automatically maintain an average potential the same as the potential of the cathode without a conductive connection thereto. 145

The anodes 4' and 4'' are, as in the case of Fig. 2, located so as to have a gap separation from the screen 5 which is comparable to the mean free path of electrons for the used gas and pressure of it, this to prevent break-down discharge between the anode of negative phase in the operating cycle as explained in connection with Fig. 2.

Auxiliary electrodes E_a and E_a' are positioned relative to the anodes 4' 4'' in a manner similar to that described with reference to Figs. 2 and 3.

The operation of the device shown in Figs. 4, 4a and 4b when connected in the circuit of Fig. 1 is readily appreciated from the inherent features of it. Considering the two discharge paths from the electron emitting cathode to the anodes 4' and 4'' respectively, and assuming that phase of the alternating current cycle when anode 4' is positive and anode 4'' is negative, the potential 20 of the cathode being midway between the anode potentials, it is apparent that the cathode drop (at least 130 volts in argon gas of about 1 millimeter mercury pressure) is eliminated from the discharge path between the cathode and positive anode 4' by reason of the electron emitting cathode, or in other words, the resistance in this path is decidedly lowered, the remaining resistance of the luminous portion and the anode drop being but small compared to the eliminated cathode drop. At the same time the cathode drop between the non-emitting shield 5' and anode 4' is maintained and since the anode drop is the same in both cases, there will be no discharge between anode 4' and screen 5 so long as the drop of 35 potential in the luminous section of the discharge path between cathode and anode does not exceed the sum of the particular cathode drop of screen 5 and the drop of the luminous section between screen 5 and anode 4'; that is, so long as the overall operating potential of the discharge path does not exceed that potential necessary to give the required velocity to ions to effectively free electrons from screen 5 upon bombardment in such way that it can act in effect as a cathode.

Considering the discharge path between the cathode and anode 4'', temporarily required to be inactive, the screen 5, charged walls of the tube, the cathode and its electron cloud, and screen 6 if used, serve to effectively prevent positive ions 50 in disturbing quantity from passing from the active section to the inactive section of the tube, so that there is no break-down ionization in this inactive portion from this source. Furthermore, anode 4'' is spaced from screen 5 a distance comparable to the mean free path of the electrons, and since this is also a point of strongest field action between screen 5 and anode 4'', the electrons from anode 4'' concentratedly escape to the screen without any effective positive ionization, 60 but merely as a pure electron current of very small intensity. Thus, when anode 4'' is so polarized in the operation as to be a cathode with respect to cathode 3' 3'', the electrons are drawn off over a short mean free path of electrons and do not move in the main path over a long distance under high potential to start a reverse discharge to the emitting cathode. It is thus possible to operate with unusually high voltages 65 without producing break down discharges.

During these intervals a negative bias is developed upon the terminals P_a P_a' of Fig. 1 due to the reaction between the anodes 4' 4'' and the auxiliary electrodes E_a , E_a' as hereinbefore described.

While we have described our invention as char-

acterized by certain embodiments of a device it is to be understood that detail changes may be made therein without departing from the spirit of our invention as defined in the appended claims.

Having fully described our invention, we claim:

1. A gas-filled discharge device having an electron emitting cathode, a plurality of co-operating anodes and a conductive screen separating said anodes from each other, said cathode being located to expose its electron field to all of said anodes, said anodes being spaced from said screen distances comparable to the mean free path of the electrons in said gas-filling, and auxiliary electrodes of appreciably smaller area than said anodes in closely spaced relation to said anodes whereby a discharge may be produced between one of said auxiliary electrodes and an adjacent anode, when no current flows between said anode and cathode.

2. A gas-filled discharge device having an electron emitting cathode, a plurality of co-operating anodes, a conductive screen separating said anodes from each other, said cathode being located to expose its electron field to all of said anodes, a discharge deflecting screen in each of the discharge paths between said cathode and the several anodes, and auxiliary electrodes of appreciably smaller area than said anodes in closely spaced relation to said anodes whereby a discharge may be produced between one of said auxiliary electrodes and its adjacent anode, when no current flows between its adjacent anode and cathode.

3. A gas-filled discharge device having an electron emitting cathode, a plurality of co-operating anodes, a conductive screen between said anodes dividing said tube into as many discharge sections as there are anodes, said cathode being located to expose its electron field to all of said anodes, a conductive screen surrounding said discharge sections, and auxiliary electrodes of appreciably smaller area than said anodes in closely spaced relation to said anodes whereby a discharge may be produced between said auxiliary electrodes and said anodes, when no current flows between said anodes and cathode.

4. A gas-filled discharge device having an electron emitting cathode, a plurality of co-operating anodes, screening means for directing the operating discharges between said cathode and said anodes, said screening means being conductively connected to said cathode, and auxiliary electrodes of appreciably smaller area than said anodes in closely spaced relation to 130 said anodes whereby a discharge may be produced between said auxiliary electrodes and said anodes, when no current flows between said anodes and cathode.

5. A gas-filled discharge device having an electron emitting cathode having a plurality of sections, a plurality of co-operating anodes, a screen dividing said device into as many discharge sections as there are anodes, each discharge section having one section of said cathode principally 140 co-operating therewith, and auxiliary electrodes of appreciably smaller area than said anodes in closely spaced relation to said anodes whereby a discharge may be produced between said auxiliary electrodes and said anodes, when no current flows between said anodes and cathode.

6. A gas-filled discharge device including a heatable electron emitting cathode having a plurality of sections, a plurality of co-operating anodes, means for dividing said device into as

- many discharge sections as there are anodes each of which sections has one of said cathode sections cooperating principally therewith, and auxiliary electrodes of appreciably smaller area than said anodes in closely spaced relation to said anodes whereby a discharge may be produced between said auxiliary electrodes and said anodes when no current flows between said anode and cathode. 80
10. A gas-filled discharge device including an electron emitting cathode, a plurality of co-operating anodes, a screen between said anodes, said cathode being located to independently expose its electron field to each of said anodes, auxiliary electrode means serving to confine the discharges between said cathode and the several anodes, and auxiliary electrodes of appreciably smaller area than said anodes in closely spaced relation to said anodes whereby a discharge may be produced between said auxiliary electrodes and said anodes, when no current flows between said anode and cathode. 85
15. A gas-filled full-wave alternating current rectifier tube including an electron emitting cathode, a pair of co-operating anodes, a conductive screen interposed between said anodes, said cathode being located in a space at one edge of said screen to expose its electron field to both of said anodes, each of said anodes being spaced from said screen a distance comparable to the mean free path of electrons in said gas-filling, and auxiliary electrodes of appreciably smaller area than said anodes in closely spaced relation to said anodes whereby a discharge may be produced between said auxiliary electrodes and said anodes, when no current flows between said anode and cathode. 90
20. A gas-filled full-wave alternating current rectifier tube including an electron emitting cathode, a pair of co-operating anodes, a conductive screen interposed between said anodes, said cathode being located in a space at one edge of said screen to expose its electron field to both of said anodes, each of said anodes being spaced from said screen a distance comparable to the mean free path of electrons in said gas-filling, and auxiliary electrodes of appreciably smaller area than said anodes in closely spaced relation to said anodes whereby a discharge may be produced between said auxiliary electrodes and said anodes, when no current flows between said anode and cathode. 95
25. A gas-filled full-wave alternating current rectifier tube including an electron emitting cathode, a pair of co-operating anodes, a conductive screen interposed between said anodes, said cathode being located in a space at one edge of said screen to expose its electron field to both of said anodes, each of said anodes being spaced from said screen a distance comparable to the mean free path of electrons in said gas-filling, and auxiliary electrodes of appreciably smaller area than said anodes in closely spaced relation to said anodes whereby a discharge may be produced between said auxiliary electrodes and said anodes, when no current flows between said anode and cathode. 100
30. A gas-filled full-wave alternating current rectifier tube including an electron emitting cathode, a pair of co-operating anodes, a conductive screen interposed between said anodes, said cathode being located in a space at one edge of said screen to expose its electron field to both of said anodes, each of said anodes being spaced from said screen a distance comparable to the mean free path of electrons in said gas-filling, and auxiliary electrodes of appreciably smaller area than said anodes in closely spaced relation to said anodes whereby a discharge may be produced between said auxiliary electrodes and said anodes, when no current flows between said anode and cathode. 105
35. A gas-filled full-wave alternating current rectifier tube including an electron emitting cathode, a pair of co-operating anodes, a conductive screen interposed between said anodes, said cathode being located in a space at one edge of said screen to expose its electron field to both of said anodes, each of said anodes being spaced from said screen a distance comparable to the mean free path of electrons in said gas-filling, and auxiliary electrodes of appreciably smaller area than said anodes in closely spaced relation to said anodes whereby a discharge may be produced between said auxiliary electrodes and said anodes, when no current flows between said anode and cathode. 110
40. A gas-filled full-wave alternating current rectifier tube including an electron emitting cathode, a pair of co-operating anodes, a conductive screen interposed between said anodes, said cathode being located in a space at one edge of said screen to expose its electron field to both of said anodes, each of said anodes being spaced from said screen a distance comparable to the mean free path of electrons in said gas-filling, a conductive coating on that part of the inner surface of said tube surrounding said interior structure, and auxiliary electrodes of appreciably smaller area than said anodes in closely spaced relation to said anodes whereby a discharge may be produced between said auxiliary electrodes and said anodes, when no current flows between said anode and cathode. 115
45. A gas-filled full-wave alternating current rectifier tube including an electron emitting cathode, a pair of co-operating anodes, a conductive screen interposed between said anodes, said cathode being located in a space at one edge of said screen to expose its electron field to both of said anodes, each of said anodes being spaced from said screen a distance comparable to the mean free path of electrons in said gas-filling, a conductive coating on that part of the inner surface of said tube surrounding said interior structure, and auxiliary electrodes of appreciably smaller area than said anodes in closely spaced relation to said anodes whereby a discharge may be produced between said auxiliary electrodes and said anodes, when no current flows between said anode and cathode. 120
50. A gas-filled full-wave alternating current rectifier tube including an electron emitting cathode, a pair of co-operating anodes, a conductive screen interposed between said anodes, said cathode being located at one edge of said screen to expose its electron field to both of said anodes, additional screens partially obstructing the direct paths between said cathode and each of said anodes, said anodes being spaced from said first screen a distance comparable to the mean free path of electrons in said gas-filling, and auxiliary electrodes of appreciably smaller area than said anodes in closely spaced relation to said anodes whereby a discharge may be produced between said auxiliary electrodes and said anodes, when no current flows between said anodes and cathode. 125
55. A gas-filled full-wave alternating current rectifier tube including an electron emitting cathode, a pair of co-operating anodes, a conductive screen interposed between said anodes, said cathode being located at one edge of said screen to expose its electron field to both of said anodes, additional screens partially obstructing the direct paths between said cathode and each of said anodes, said anodes being spaced from said first screen a distance comparable to the mean free path of electrons in said gas-filling, and auxiliary electrodes of appreciably smaller area than said anodes in closely spaced relation to said anodes whereby a discharge may be produced between said auxiliary electrodes and said anodes, when no current flows between said anodes and cathode. 130
60. A gas-filled full-wave alternating current rectifier tube including an electron emitting cathode, a pair of co-operating anodes, a conductive screen interposed between said anodes, said cathode being located at one edge of said screen to expose its electron field to both of said anodes, additional screens partially obstructing the direct paths between said cathode and each of said anodes, said anodes being spaced from said first screen a distance comparable to the mean free path of electrons in said gas-filling, and auxiliary electrodes of appreciably smaller area than said anodes in closely spaced relation to said anodes whereby a discharge may be produced between said auxiliary electrodes and said anodes, when no current flows between said anodes and cathode. 135
65. A gas-filled full-wave alternating current rectifier tube including an electron emitting cathode, a pair of co-operating anodes, a conductive screen interposed between said anodes, said cathode being located at one edge of said screen to expose its electron field to both of said anodes, additional screens partially obstructing the direct paths between said cathode and each of said anodes, said anodes being spaced from said first screen a distance comparable to the mean free path of electrons in said gas-filling, and auxiliary electrodes of appreciably smaller area than said anodes in closely spaced relation to said anodes whereby a discharge may be produced between said auxiliary electrodes and said anodes, when no current flows between said anodes and cathode. 140
70. A gas-filled full-wave alternating current rectifier tube including an electron emitting cathode, a pair of co-operating anodes, a conductive screen interposed between said anodes, said cathode being located at one edge of said screen to expose its electron field to both of said anodes, additional screens partially obstructing the direct paths between said cathode and each of said anodes, said anodes being spaced from said first screen a distance comparable to the mean free path of electrons in said gas-filling, and auxiliary electrodes of appreciably smaller area than said anodes in closely spaced relation to said anodes whereby a discharge may be produced between said auxiliary electrodes and said anodes, when no current flows between said anodes and cathode. 145
75. A gas-filled rectifier tube for alternating current including an electron emitting cathode, a co-operating anode spaced from said cathode a
11. A gas-filled rectifier tube for alternating current including an electron emitting cathode, a co-operating anode spaced from said cathode a
12. An electric discharge tube containing a gas, a plurality of anodes, a barrier interposed between said anodes, said barrier being spaced a distance from said anodes comparable to the mean free distance of said gas, a thermionic cathode interposed between said anodes, and auxiliary electrodes of appreciably smaller area than said anodes in closely spaced relation to said anodes. 150
13. A gaseous rectifier tube comprising a cathode adapted to be heated, a plurality of anodes, means disposed between said anodes for preventing a gaseous discharge therebetween, and an auxiliary electrode adjacent one of said anodes and shielded by said anode with respect to a gaseous discharge between said auxiliary electrode and said cathode. 155
14. A gaseous discharge tube comprising a thermionic cathode, an anode, and an auxiliary electrode of small dimensions and area relative to those of the anode, said anode being disposed between said cathode and said auxiliary electrode. 160
15. An electric discharge tube comprising a thermionic cathode, an anode having an extensive surface exposed to said cathode, and an auxiliary unheated electrode of relatively small surface disposed adjacent said anode and shielded by the anode from the space between said cathode and anode. 165
16. A full-wave rectifier tube comprising a thermionic cathode, a plurality of anodes each having an extensive surface exposed to said cathode, and an auxiliary unheated electrode of relatively small surface disposed within said tube out of the main discharge paths between said cathode and said anodes but in discharge relation to one of the anodes. 170
17. An electron discharge device comprising a thermionic emissive electrode, an unheated electrode having a relatively small surface, and an electrode having an extensive continuous surface forming a discharge preventing shield between the aforementioned electrodes and adapted to act alternately as anode to said thermionic electrode and as cathode to said small unheated electrode. 175
18. An alternating current rectifier comprising a discharge tube including a main discharge anode, a thermionic cathode, and an auxiliary anode small relative to the main anode and spaced therefrom, the said auxiliary anode forming with the main anode an auxiliary rectifying discharge path which is independent of the main discharge path between the main cathode and anode during periods of inactivity of the latter as an element in the principal rectifying function. 180
